UNITED STATES PATENT OFFICE.

VINCENT PACE, OF BROOKLYN, NEW YORK.

STRETCHING AND FORMING DEVICE.

Application filed December 29, 1927. Serial No. 243,292.

The invention relates to stretching and forming devices for garments and has for its object to provide a self-adapting device of this type for efficiently stretching and forming 5 predetermined parts of garments such as coat sleeves while said garment sections are being steam or otherwise operated upon.

The invention contemplates particularly the production of a device adapted to be inserted into the sleeve of a coat or the like for the purpose indicated above and capable of being easily removed independently of any manipulation of the coat sleeve, subsequent to the steaming or other treatment thereof. 15 Other more specific objects will appear from the description hereinafter and the features of novelty will be pointed out in the claims.

In the accompanying drawings which illustrate an example of the invention without defining its limits, Fig. 1 is an elevation of the device in a completely expanded condition; Fig. 2 is a similar view showing the device in a collapsed condition; Fig. 3 is a section on the line 3—3 of Fig. 1, and Fig. 4 is a perspective 25 view of a conventional coat with the device inserted in one of the sleeves thereof.

For the purpose of illustrating and describing the invention, the device is shown in a form in which it is used for stretching and 30 forming sleeves for which purpose it is particularly adapted. It will be understood, however, that this is not intended to define the limits of the invention, which obviously may be used to stretch and form the legs of 35 conventional trousers and other articles of wearing apparel or the like.

In its illustrated form, the device comprises a pair of opposed stretching members shown in the form of bars 10 and 11, the outer edges 40 of which are rounded transversely as shown in Fig. 2, and curved longitudinally as illustrated in Fig. 1. In the sleeve stretching and forming device of the illustrated example, the bars 10 and 11 are located in spaced parallel relation and are normally forced apart through the medium of a suitable yielding means located between said bars. In the form shown in the drawing, this yielding 45 means comprises oppositely bowed springs 12, each pivotally connected at one end, as shown at 13, with the respective bars 10 and 11. The opposite ends of the springs 12 are in slidable engagement with the inner portions of said bars 10 and 11, so that said springs are free to 50 accommodate themselves to any change in

the position of said bars in directions toward and away from each other. In the preferred arrangement, the pivoted ends 13 of said springs are located in recesses 14 formed in the bars 10 and 11, while the opposite free ends 60 of said springs are curved and slidably accommodated in recesses 15, the bottoms of which are preferably curved so as to develop no interference to the freedom of movement of the spring ends. The springs 12 are in 65 engagement with each other and are preferably connected in any suitable manner, as for instance, by means of a suitable clip 16, located at an intermediate point of the springs. 70

The bars 10 and 11 are flexibly connected with each other at one end by suitable flexible connecting means so that as a compressing pressure is exerted on the free ends of the bars, the aforesaid flexible connecting means will 75 operate to cause the opposite ends of said bars to also approach each other, against the tension of the springs 12.

In the illustrated example, the flexible connecting means comprises end members 17, flexibly connected with each other, for instance, by means of a hinge 18 and having their free ends flexibly connected with the ends of the respective bars 10 and 11, for instance, by means of pivotal connections or hinges 19. 80 The end members 17 are curved, and together form an articulated arched continuation of the bars 10 and 11 so that the device as a whole presents the form of an inverted U when viewed as in Fig. 1. While it is preferred to 85 have the inner surfaces of the bars 10 and 11 parallel with the outer surfaces of said bars, this is not absolutely necessary. 90

In utilizing the device in its illustrated form, a compressing pressure is exerted upon the bars 10 and 11 at their free end portions to an extent sufficient to overcome the tension of the springs 12 and to pivotally collapse the end member 17 and to thus adjust the bars 10 and 11, for instance, to the position illustrated in Fig. 2. In this collapsed condition, the device is capable of being easily inserted into the sleeve 20 of a coat and after having been fully inserted therein is permitted to expand to the condition illustrated in 100 Fig. 4. In this position, the springs 12 force the bars 10 and 11 apart and thereby stretch the coat sleeve into form so as to permit it to be placed in this condition between the customary press board and steam board of the 105 110

conventional pressing and steaming machine. It will be understood that the device is so designed that this stretching action upon the coat sleeve will be effected in an efficient manner, without injury to the fabric of which the latter is made, or without undue strain upon the stitching whereby the same is sewed together. The arched end members in addition to their other functions serve also to 5 form the shoulder end of the sleeve which said end members are designed to fit, as is clearly illustrated in Fig. 4. It will be noted that the device is of sufficient length to cause the free ends of the bars 10 and 11 to project 10 beyond the end of the sleeve when said device occupies its operative position, as shown in Fig. 5. When it is desired to remove the device, a compressing pressure is exerted on the exposed end portions of the bars 10 15 and 11 to force the latter together and to collapse the end members 17 and thereby also force the inner ends of the bars 10 and 11 towards each other against the tension of the springs 12. In this collapsed condition 20 which may extend beyond the position indicated in Fig. 2, the device is easily removable from the sleeve. It will be noted that the collapsing of the device in the sleeve is brought about without requiring the sleeve 25 itself to be touched and without necessitating any pressure to be exerted on the sleeve to bring about such collapse. This arrangement avoids the possibility that the sleeve may be distorted or wrinkled in the act of 30 removing the device and after having been steamed and pressed, it being understood that the device may be permitted to remain in the sleeve for any desired length of time. The transversely round outer edges of the bars 10 35 and 11 serve to form rolled edges in the sleeve, instead of sharp creases; obviously the form of these edges may be changed to meet 40 any special conditions which may exist.

While the description relating to the use 45 of the device has been made specifically in connection with coat sleeves, it will be obvious that the same description applies to the device when designed for use with the legs of trousers, ladies' skirts, or other articles 50 of wearing apparel or the like for which it is adapted.

The device is extremely simple in construction and requires no skill in its operation.

Various changes in the specific form shown and described may be made within the scope 55 of the claims without departing from the spirit of the invention.

I claim:

1. A self-adapting stretching and forming device of the kind described, comprising a 60 pair of opposed stretching bars of predetermined form to fit a portion of a garment for which the device is designed, yielding means located between said bars whereby the latter are normally forced apart, and end 65 members pivotally connected with each other and extending between and flexibly connecting said bars with each other and forming an articulated continuation thereof at one end of the device. 70

2. A self-adapting stretching and forming device of the kind described, comprising a pair of opposed stretching bars having their outer edges transversely rounded and curved lengthwise in parallel relation to each other, 75 yielding means mounted between said bars whereby the latter are normally forced apart, and curved end members pivotally connected with each other to form an articulated arch extending between and flexibly connecting 80 said bars with each other at one end of the device.

3. A self-adapting stretching and forming device of the kind described, comprising a pair of opposed stretching bars having their 85 outer edges transversely rounded and curved lengthwise to fit the conventional curvature of a coat sleeve, oppositely bowed springs pivotally connected at one end with said bars, and having their opposite ends in slidable engagement with the inner faces of said 90 bars, said springs exerting a tension whereby said bars are normally forced apart, means whereby said springs are connected with each other at an intermediate point, and curved 95 end members hinged together to form an arch and each having its free end hinged to one of said bars.

In testimony whereof I have hereunto set my hand.

VINCENT PACE.
